UNITED STATES PATENT OFFICE

RICHARD LEONARD ARNOLD SCHOEMAKER, OF DELFT, NETHERLANDS

METHOD OF TELEGRAPHING IN MORSE CODE AND APPARATUS THEREFOR

Application filed March 20, 1928, Serial No. 263,040, and in the Netherlands May 20, 1927.

Telegraphy by Morse code is generally effected by means of the tapping key known as the Morse key, or by means of automatic or semi-automatic transmitting apparatus 5 operating at a higher speed.

The defect of the Morse key hitherto used, is that it can only be operated efficiently by highly expert telegraphists. If the taps are not very regularly timed and proportioned 10 irregular intervals occur between the symbols, or the dots and dashes are not of regular length, so that errors may easily arise in decoding.

The wholly or semi-automatically actuated 15 transmitters besides being expensive have the disadvantage that they are difficult to adjust and are not easily portable, so that they are unsuitable for small telegraph offices and railway stations, and special difficulties attend their use on ships, or for the purpose 20 of military communication. Furthermore, the operation of such complicated apparatus requires a skilled staff.

My invention provides a method and apparatus for transmitting telegraphic messages in Morse code, whereby the dots, dashes and intervals are produced regularly in the proper sequence independently of the degree of skill of the telegraphist. A further advantage of the invention is that the messages are more rapidly transmitted than with 30 the Morse keys hitherto known.

As compared with the known wholly and semi-automatic apparatus the invention has 35 the advantage of being cheaper, though capable of more rapid transmission.

These advantages are attained according 40 to the invention by producing the transmitting impulse by causing a contact member to move over a series of contacts, or a series of contacts to move over a single contact.

The invention is characterized by the following features:—

(a) The Morse signs are produced by to 45 and fro movement of a movable contact member.

(b) Movement of the contact member starts from a zero position the outward and return movement on one side of this zero position 50 causing the transmission of one or more dots,

with intervals, and the outward and return movement of the contact member on the other side of the zero position causing one or more dashes to be transmitted with intervals. By combining movements to either side of the 55 zero position, complete Morse code characters are transmitted.

(c) The combination of dots, dashes and spaces of predetermined length are automatically transmitted as Morse characters by the 60 movement of one contact member on another specially constructed contact member. Uniform movement of the movable contact member over the stationary contacts, produces makes and breaks of regular duration so that 65 mutilation of the characters transmitted is practically precluded.

(d) The duration and uniformity of the movement of the contact member are functions of the distance from the axis of rotation to the centre of the handle used for manipulating the contact member, and they are also functions of the angle traversed when the handle is moved from the initial 70 to the final position.

(e) The closing and opening of the circuit is effected during the continuous movement of the contact member, by means of a contact passing either over a contact strip having a series of insulating strips on it (or vice 75 versa) or over a correspondingly constructed contact bar.

(f) The position of the handle at which the outward movement ends and the return movement commences, is not only ocularly 80 observable but can also be indicated by touch and by the ear. A scale is provided for visual observation and for control by touch and by ear. It may arrange springs or spring actuated members which snap into depressions. The pointer and figures on the scale may be luminous so as to be visible in the dark, particularly if audible detection of the 85 transmitted signals is not desirable or possible.

(g) The apparatus may also be provided with a recording device for recording at the transmitting station the Morse messages transmitted.

(h) The apparatus may also be provided 100

with a "stand-by" transmitter which can be used for duplicating purposes in case the recording device is out of order.

5 The accompanying drawing illustrates two modifications of apparatus according to the invention.

Figures 1 to 5 show a Morse transmitter and Figures 6 to 16 show a Morse transmitter combined with a recording device and a 10 "stand-by" transmitter.

Fig. 1 is a perspective view of the Morse transmitter.

Fig. 2 is a plan view of the transmitter shown in Fig. 1, with the handle removed for 15 clearness.

Fig. 3 is a cross section on the line U—U of Fig. 1.

Fig. 4 is a cross section on the line V—V of Fig. 3.

20 Fig. 5 is a plan view of the handle.

Fig. 6 is a perspective view of the Morse transmitter combined with a recording device and "stand-by" transmitter.

Fig. 7 is a plan view, with the lever and 25 pointer omitted.

Fig. 8 is a cross section on the line W—W of Fig. 6.

Fig. 9 is a plan view of the lever and pointer.

30 Fig. 10 is a front elevation and

Fig. 11 a side elevation of a contact member for transmitting dots.

Fig. 12 shows a contact member in front 35 elevation for transmitting dashes.

Fig. 13 shows the movable element for use with the contacts according to Figs. 10 to 12.

Fig. 14 is a cross section on the line x—x of Fig. 8.

Fig. 15 is a cross section on the line y—y of Fig. 8.

40 Fig. 16 shows another modification of the recorder in three projections.

The principal elements of the apparatus are a contact member manipulated by hand 45 and a series of contacts over which this contact member is reciprocatable.

The series of contacts, constituting a contact strip, in the modification according to Figs. 1 to 5 is differently constructed from 50 that in the modification according to Figs. 6 to 16.

The series of contacts according to the first modification (Figs. 1 to 5) is in the form of a rigid contact strip 2 having plates of insulating material 3 let into it. The plates 3 are so disposed on the contact strip, that when the movable contact member passes uniformly over the conducting parts 4 and the plates 3, the circuit is alternately closed and opened 60 with the correct intervals, for producing current impulses according to the Morse code.

The contact strip 2 is insulated except as regards its connection to the telegraph line by means of screws 5.

55 The movable contact comprises a member

7 having mounted therein a spring loaded pin 6. This conductive member 7 is provided with a detachable handle 1, and is connected to the other pole by means of members 8 and balls 9, which make contact with a conductor 10.

A scale 11 is provided, reading from 0 to 5 on each side of the zero position in what may be called the positive and negative directions respectively.

75 The markings on the positive side of the scale indicate the positions at which the contact movement is reversed, for transmitting one or more dots with the proper intervals between them, and the markings on the negative side provide the same indication with regard to the dashes.

A pointer 12 is fixed to the member 7, for indicating the position of the pin 6.

80 The points of reversal, besides being clearly indicated as described, may also be indicated by touch and by ear. For this purpose a spring 13 is fixed to the member 7, and snaps into small depressions 14 at the edge 15 of the scale during the movement of the member 7.

85 The spring actuated pin 6 fulfills the same purpose by engaging the depressions disposed approximately half way between the contacts 4.

90 In order to ensure practically effortless and regular operation of the transmitter the operator's hand should pass though as small a path as possible when transmitting. This is most conveniently effected if the wrist is 95 stationary and the hand pivots about the wrist in the manner of a pendulum. For this purpose the distance from the axis M to the handle 1 should be about 10.5 cm., and the maximum angle through which the contact member is swung should be from 37.5° to 100 40°.

95 The transmitter is operated in the following manner. The movable contact member is moved by means of the handle from the central opening of the contact strip 2, i. e. from the zero position, so that one or more dots or dashes are transmitted the contact being moved approximately to the centre of a short or long contact strip or of an intermediate plate of insulating material, and then back to the zero position.

100 The turning points marked on the scale adjacent to the centre of the plates 3 of insulating material are denoted by even numbers, and the turning points adjacent to the centre of the contact strips 4 are denoted by 105 odd numbers.

110 If it is desired to transmit a dash the pointer 12 is moved by the handle 1 from the zero position to position 1 on the side provided with long contact strips, and returned to the zero position. If two dashes are to be transmitted consecutively the pointer 12 is moved to the same side of the zero position.

tion to position 2 and back to the zero position. In the same manner the pointer 12 is moved to and from positions 3, 4 or 5 when it is desired to transmit three, four or five dashes consecutively. The same procedure is followed on the other side of the zero position for transmitting dots, where the turning points are similarly indicated.

If it is desired to transmit a combination of dots and dashes, for example • • - - • •, the pointer 12 is first moved from the zero position to position 2 (dot), then to position 2 (dash), then to position 2 (dot) and finally returned to the zero position.

The turning points are not only denoted by the numbers on the scale, but are also indicated by means of a spring catch 13 or the like, which clicks into and out of the depressions or notches 14. The resiliently mounted pin 6 may also be made to engage notches or depressions.

The numbers on the scale and the pointer may be rendered luminous, so that anyone unskilled in telegraphy may transmit Morse signs in the dark. Expert telegraphists are able to transmit Morse signs without such assistance, however the invention has the advantage that the turning points are clearly indicated by the engagement of the resilient member in the notches.

The modification according to Figs. 6 to 16 differs from that in Figs. 1 to 5 mainly in that the contacts and the contact strip are differently constructed. In the modification according to Figs. 6 to 16 the movable contact is in the form of a contact cylinder 16 rotatably mounted on the pin 17, the said cylinder closing the circuit as it rolls over the raised contacts 18 of the plungers P (Fig. 13).

The pin or contact lever 17 is pivotally connected at 20 to the pointer 19 (Figs. 8 and 9). The lever 17 is depressed by a spring 21, and can be adjusted by a screw 22 provided with a lock nut. The pointer 19 is swingable about the axis 23 fixed to the base 24.

The row of contacts in this modification is in the form of a group of contacts or a row of teeth. In the first case the row of contacts consists of a number of spring plungers P, whose upper ends A or B are adapted for transmitting dashes or dots respectively.

Each of these resilient contact members consists of a plunger P, a housing 25 and a helical spring 26 within the said housing. The spring 26 acting on the flange 27 of the vertically slideable plunger P tends to keep the latter in its uppermost position, so that the contact surfaces 18 are raised. The movement of the plunger is restricted by the slot 29 in it and the pin 28 fixed to the housing 25. The lower end of the stem 30 of the plunger is provided with a sharp point 31.

When the pointer is moved laterally by

the handle the contact cylinder 16 depresses each plunger in turn for a period depending on the length of the contact surface 18. This length depends on whether the contact is adapted for transmitting dots or dashes. The sharp point or needle at the lower end of the plunger impresses or perforates the recording web below the instrument, and in this way records on the web the Morse signs transmitted. The recording web must thus be guided by the transmitter in a direction which does not deviate greatly from the direction M—O. The Morse signs appear on the recording web strung together in groups.

The modification shown in Fig. 16 enables the Morse signs to be recorded in rectilinear groups.

For this purpose, instead of being provided with sharp pins 31, the plungers are provided with rounded strikers, which act on the two-armed levers 33. The latter are rotatable about the sharp ridges 40. These ridges 40 are preferably arranged on the bar 39 in such manner that they are perpendicular to the various levers 33, while the connections between the sharp ridges 40 extend above them to form lateral guides for the levers 33.

When upon closure of one of the contacts the striker 31 of the plunger P is depressed on to one arm of the lever 33, for example into a depression or on a nose on said lever, this arm is depressed while the arm on the other side of the sharp ridge 40 is raised.

When the arm of the lever is not depressed by the respective strike 31, the other arm rests on a bar 42. The bar 42 is provided with ribs 41 acting as lateral guides during the downward movement of one arm and the upward movement of the other arm. These levers actuated by the plungers P are located immediately below a single-armed lever 34 provided with a marking roller 35, the said lever being rotatable about the point 36, and being held in the position of rest by means of a spring.

If, owing to the action of the plunger P on the associated lever arm, the lever arms deflected by the plunger P below the bar 42 are raised, the lever 34 is rotated about the point 36, and the roller 35 is raised and pressed against the paper web on the guide rollers 38, whereby the web is perforated, impressed or inscribed on so long as the plunger P depresses one of the levers 33.

Each plunger P acts on a lever 33 associated with it. All the levers 33 act on the same lever 34, so that the recording web is marked by the same roller 35, whichever plunger is depressed and whichever lever 33 is operated.

The marking roller 35 is always pressed with equal force against the paper web, in spite of the differences between the levers 33 or the varying distances of the point of en-

gagement of the lever 33 on the lever 34 from the axis of rotation, if, (1) the bar 39 and (2) the axes of rotation represented by the sharp ridges 40 of the levers 33, are so disposed that the roller 35 is always raised to the same extent from its position of rest.

This is accomplished by so proportioning the arms 33 in each case, that the upward movements of the arms 33 deflected by the 10 plungers P are so determined by the said proportioning and differ from each other in such manner that in view of the various points of engagement of the levers 33 on the lever 34, the roller 35 is always raised to the same 15 extent.

The contact ridge of each resilient contact has a shallow notch approximately at its centre, for indicating to the touch or to the ear the turning points of each swinging 20 movement.

The slightly conical roller 33 is used for supporting the lever 19. This roller also serves as a contact member for a reserve transmitter. For this purpose the roller 33 25 is guided over a contact strip 34, which may be dented. This contact strip is subdivided, as described above, into contact making and breaking portions, wherein the turning points are disposed approximately at the centre of 30 each portion and coincide with the markings on the scale.

The turning points of this reserve transmitter are made perceptible to the touch and the ear by the spring 12, provided with a 35 rounded head engaging depressions in the scale. If, for any reason, the telegram, transmitted is not recorded on the recording web below the transmitter, or if a breakdown occurs, for example, as the result of failure 40 of one of the plungers P, the reserve transmitter can be used.

In the modification according to Figs. 6 to 15 two kinds of contacts are used for transmitting Morse signs. These contacts differ 45 in that the contact ridges B, for transmitting dots, are one third as long as the contact ridges A for transmitting dashes. In this modification also the contacts for transmitting dashes and those for transmitting dots, 50 are confined respectively to one or other side of the zero position (Fig. 7). The contacts A and B are all connected by means of contact bars 35.

Morse signs are transmitted in the modification according to Figs. 6 to 16, by moving 55 the lever 19 provided with a pointer 12 as described in connection with Figs. 1 to 5.

Having now particularly described and ascertained the nature of my said invention and 60 in what manner the same is to be performed, I declare that what I claim is:—

1. The method of telegraphically transmitting messages in Morse code by the means 65 of electric impulses in which all the symbols and characters of the Morse alphabet as well

as every combination of the same are produced by moving one single contact over one single path of contacts or the reverse, and wherein movement of the movable contact in one direction from the starting position at zero and then back to said starting position, transmits a dot or dots, with the proper intervals, and its movement from the zero position in the opposite direction, and back to the zero position, transmits a dash or dashes, with the proper intervals, combinations of dots and dashes being produced by combinations of movements on both sides of the zero position.

2. Apparatus for telegraphically transmitting messages in Morse code comprising a fixed contact unit embodying a series of spaced contact elements, each of a length commensurate with the dot signal of the code, and a series of spaced contact elements each of a length commensurate with the dash signal of the code, relatively adjacent elements of each series being spaced apart, the relatively adjacent end elements of the two series being mutually spaced, and a contact member including a contact element and mounted for movement to bring the said contact element thereof to a zero position within the space between the said relatively adjacent contact elements of the said two series and selectively into contact with one or more of the elements of either series.

3. Apparatus for telegraphically transmitting messages in Morse code comprising a fixed contact unit embodying a series of spaced contact elements each of a length commensurate with the dot signal of the code, and a series of spaced contact elements each of a length commensurate with the dash signal of the code, relatively adjacent elements of each series being spaced apart, the relatively adjacent end elements of the two series being mutually spaced, and a contact member including a resiliently supported contact element, the said member being mounted for movement to bring the said contact element thereof to a zero position within the space between the said relatively adjacent contact elements of the said two series and selectively into contact with one or more of the elements of either series.

4. Apparatus for telegraphically transmitting messages in Morse code comprising a fixed contact unit embodying a series of spaced contact elements each of a length commensurate with the dot signal of the code, and a series of spaced contact elements each of a length commensurate with the dash signal of the code, relatively adjacent elements of each series being spaced apart, the relatively adjacent end elements of the two series being mutually spaced, and a contact member including a contact element and mounted for movement to bring the said contact element thereof to a zero position within

the space between the said relatively adjacent contact elements of the said two series and selectively into contact with one or more of the elements of either series, the said movable contact member comprising a lever, and
5 a yieldably supported contact cylinder mounted thereon.

5. Apparatus for telegraphically transmitting messages in Morse code comprising a fixed contact unit embodying a series of spaced contact elements each of a length commensurate with the dot signal of the code, and a series of spaced contact elements each of a length commensurate with the dash signal of the code, relatively adjacent elements of each series being spaced apart, the relatively adjacent end elements of the two series being mutually spaced, and a contact member including a contact element and mounted for movement to bring the said contact element thereof to a zero position within the space between the said relatively adjacent contact elements of the said two series and selectively into contact with one or more of the elements of either series, each of the contact elements of the two series comprising a plunger, a spring yieldably supporting the same in elevated position, and a contact upon the upper end of the plunger having a curved depression in its upper side.

30 In testimony whereof I have affixed my signature.
